FUEL BURNER

William F. Steinmetz, New York, N. Y.

Application May 5, 1934, Serial No. 724,163

13 Claims. (Cl. 126—170)

This invention relates in general to fuel burner apparatus and more particularly to an improved grate construction and operation.

Heretofore in burning solid fuels by use of natural draught methods in furnaces and heaters fitted with grate systems of the conventional type, difficulties have been encountered that must be overcome in order to accomplish efficient combustion. These difficulties arise by reason of a lack of provision for a sufficient volume of air to pass through the fuel bed, the air being poorly distributed and not brought into proper contact with the burning fuel. Hence the temperature of the air required for efficient combustion is not kept up to the high point necessary to ignite and consume the highly inflammable hydrocarbonic gases being distilled out of the burning fuel. In the previous attempts in the prior art to accomplish smokeless combustion, the grate structure is not so arranged as to insure a volume of air reaching the burning fuel that is definitely in excess of the amount required for complete combustion. There has heretofore been lacking the appreciation of the necessity for oscillating a sufficient area of the fuel supporting grate surfaces. In many instances there is inadequate means for discharging the ashes when necessary. In those devices employing oscillating grate members they are not arranged so as to effectively agitate the ash accumulating on the fuel supporting surfaces and insure their gravitation to the lower levels of the grate system from which they should be discharged. This failure of design has a marked tendency to retard and reduce the admission and volume of air necessary for efficient combustion.

It is therefore specifically among my primary objects of invention to provide a grate structure capable of supporting a considerable quantity of burning fuel and comprised of relatively moving parts with means for so moving the parts that the agitation and removal of ash deposit from all parts of the grate structure and into the ash pit may be insured by means of a simple single manual operation.

A more general object of my invention is to provide a grate system that will increase the efficiency of furnaces and heaters, by rendering more complete and economical the combustion of solid fuels, more especially the less expensive and more finely crushed sizes, and reducing to a minimum the smoke content escaping through the flue to the chimney, especially with the use of bituminous fuels, thus decreasing the smoke nuisance.

Another object is to provide improved means to agitate the bed of burning fuel to more effectively dislodge the ash that chokes the apertures between grate bars and accumulate adjacent to the grate surfaces and to more rapidly discharge the ash to the ash pit, thereby rendering a freer admission of air through the grate structure to aid combustion.

Another object is to materially increase the area of the grate surface in proportion to the horizontal area of the combustion chamber of heaters, thus supplying a more liberal quantity and improved distribution of the air supply; hence more oxygen to the burning fuel, part of which becomes preheated, passes up, through, around and above the fuel bed in support of combustion, increasing ignition of the highly inflammable mixtures of the distilled hydro-carbon gases, thereby rendering more complete the combustion and intensifying the heat generated.

Another object is to provide means for maintaining a comparatively deep bed of fuel, so as to increase the interval between stoking periods, in contrast to the conventional flat grate systems wherein the finer crushed sizes can be burned only by maintaining a very shallow fuel bed, necessitating frequent stoking periods.

Another object is to provide an improved and simple extensible frame to support the superposed fuel supporting grate members that can be readily adjusted to conform to the various size heaters, utilizing the fixtures provided in the combustion chambers wherein are employed conventional grate bar systems.

Another object is to provide an extensible shaker device that can be adjusted to position in the identical apertures provided in the front or side of various make heaters to receive the shank formed ends of their conventional grate bars and adapted for use of the common shaker lever, thus eliminating the necessity of any alteration of the heater for installation.

With these and other ends in view I propose as a preferred construction to provide a central fuel supporting grate section in the general shape of a dome with a plurality of vertical slots therein. The dome may have a plurality of fin-like members projecting outwardly from its outer convex fuel supporting surface to more efficiently agitate the fuel and ash adjacent thereto when the dome is oscillated or rotated about its vertical axis. Arranged preferably immediately annularly of the dome are a plurality of horizontally disposed rocking or dumping grates each movable about a substantially central hori-

zontal pivot. Arranged preferably immediately annularly of these rocking grates is a substantially vertical or upwardly outwardly inclined basket shaped fuel supporting grate. This basket is preferably comprised of a plurality of removable and interchangeable sections for convenience in installation. I also propose to provide a single manually operated means to oscillate all three of these distinct grate units simultaneously. The dome and basket shaped units oscillate about a common vertical axis, preferably in opposite directions, while the horizontally disposed rocking grates each oscillate about its individual horizontal axis.

15 This means for oscillating simultaneously every member of the entire fuel supporting surface, effectively agitates the fuel bed and efficiently dislodges the ash that normally collects adjacent the grate surfaces and adhere to the apertures formed in same, and also provides for a ready discharge of ash into the ash pit when necessary or desired.

The general conformation of the entire fuel supporting surface very materially increases the 25 grate surface area, the central dome shaped member being liberally provided with slotted apertures and having a liberal area relative to the total horizontal area of the combustion chamber, it being substantially vertically disposed over the 30 greater proportion of its height, and projecting well up into the combustion chamber.

The ash shaking system when operated opens up the fuel bed, permitting the air to enter, and aids the escape from same of the hot hydro-carbon 35 gases to the upper levels of the combustion chamber, there to mix with and ignite, the gases being distilled from the upper surface of the fuel bed in support of more efficient combustion, thus generating more intense heat.

40 The manual means to oscillate the system may be so devised that the shank formed on its outer end to receive the usual common hand shaker lever, can be adjusted to position in the identical place formerly occupied by the shank of the 45 replaced conventional grate bars of heaters, requiring no alteration of the heater for installation, it being arranged to utilize the apertures provided in the front or side of heaters for their usual common shaker lever.

50 The above and other features of this invention together with the various details of construction and combination of the parts will now be more particularly described by reference to the accompanying drawings and pointed out in the 55 claims.

In the drawings:—

Figure 1 is a partially cut away plan view of the extensible supporting bars.

Figure 2 is a sectional elevation view on the 60 plane of line 2—2, Figure 1.

Figure 3 is a sectional elevation view on the plane of the line 3—3, Figure 1.

Figure 4 is a cross section on plane of line 4—4, Figure 1.

65 Figure 5 is an elevational view of the extensible shaker device.

Figure 6 is an elevational view in the direction of line 6—6, Figure 5.

70 Figure 7 is a cross section on the plane of the line 7—7, Figure 5.

Figure 8 is a plan view of the upper member of the shaker device on the plane of the line 8—8, Figure 5.

75 Figure 9 is a plan view of the lower member of

the shaker device on the plane of the line 9—9, Figure 5.

Figure 10 is a longitudinal section on the plane of the line 10—10, Figure 6.

Figure 11 is a sectional elevation of the super- 5 posed grate system with supporting bars omitted on the line 11—11, Figure 12.

Figure 12 is a partially cutaway plan view of Figure 11 with supporting bars omitted.

Figure 13 is a fragmentary typical cross section 10 on the plane of the line 13—13, Figure 11, with supporting bars omitted.

Figure 14 is a partially fragmentary perspective view of entire assembly of the fuel burner.

Referring more particularly to the drawings the member 1' is provided with a journalled end 2 for insertion in the conventional burner socket for supporting the grate and is cast with a spindle 20 for attachment to a shaker device, later to be described. Assembled members 1', 1 and 1, 1 respectively are interlocked by having wedge shaped lugs 3 formed on their inwardly disposed extremities which are inserted in the slotted apertures 4 having chamfered or beveled surfaces 5 causing the lugs 3 and the slots 4 to position in male and female relationship; the slotted apertures 4 being enlarged by cutting away the chamfered surfaces 5 at 6 to form entry for the lugs 3 which are dimensioned to fit rather snugly in the apertures 4, Figure 4, thus permitting the bars 1', 1 and 1, 1, respectively to slide longitudinally in engagement with one another. When they are adjusted to their required extent they are locked in position by the bolt 7. Transversely disposed in relation and secured to the assembled bars 1', 1 and 1, 1 respectively are two extensible tie bar assemblies (identical in construction) each consisting of two bars 8 and one bar 9; the members 8 and 9 are interlocked by having the upwardly projecting wedge shaped lugs 14 formed 40 on both ends of the member 9 which are inserted in the slotted apertures 15 having chamfered surfaces 16, causing the lugs 14 and the slots 15 to position in male and female relationship, the slotted aperture 15 being enlarged by cutting away 45 the chamfered surface 16 and 17 to form entry for the lugs 14 which are dimensioned to fit rather snugly in the apertures 15, thus permitting the members 8 and 9 to slide longitudinally in engagement with one another. When the assembly of members 8 and 9 are adjusted to their required extent, they are locked in position by the bolts 18 passing through the apertures 15 and 19 of members 8 and 9 respectively. Extending downwardly on the outwardly disposed extremity 50 of the members 8 are the flanges 10 provided with the apertures 11 to receive the bolts 12 affording means to secure the members 8 to the bars 1', 1 and 1, 1 respectively. Projecting outwardly, molded on flanges 10 are the lugs 13 dimensioned and adapted to enter the slotted apertures 4 to insure the bars 8 against downward vertical displacement and rotation relative to bars 1', 1 and 1, 1.

Bolts 18 also pass through the slotted apertures 65 40 in the flange 39, (Figures 11, 13 and 14) of the base unit 38, thus acting in the dual capacity of locking members 8 and 9 into a rigid bar and securing the superposed grate structure (hereinafter to be described) to said assembly of the 70 members 8 and 9 which in turn are secured to supporting bars 1', 1 and 1, 1. The extensible supporting bars 1', 1 and 1, 1 in combination with the tie bar assemblies (consisting of the members 8 and 9) form an adjustable rectangular and 75

horizontally disposed supporting frame, the rectilinear elements of which are adjustable laterally.

The extensible shaker device, Figures 5, 6, 7, 8, 9, 10 and 14, consisting of the assembly of the members 25 and 26, is adapted to house the spindle 20 and is arranged with the outwardly projecting flanges 21 and 22 provided with the apertures 23 and 24 respectively therein to match 10 up for insertion of the bolts 24' to secure the upper member 25 to the lower member 26. The spindle 20 (cast integral with bar 1') is arranged with a plurality of equally spaced teeth 27 adapted to position in male and female relation with the 15 plurality of equally spaced recesses 28 (Figure 10) formed in the lower member 26, thus affording means to retain and mount assembly of the members 25 and 26 in a plurality of positions on the spindle 20. Integral therewith and extending outwardly on the upper member 25 and co-axial with the longitudinal axis of the spindle 20, Figures 10 and 14, is a tapered shank 29 (either triangular or rectangular in cross section) adapted to receive the usual common hand shaker lever 20. Integral therewith and extending outwardly on the upper member 25 and co-axial with the longitudinal axis of the spindle 20, Figures 10 and 14, is a tapered shank 29 (either triangular or rectangular in cross section) adapted to receive the usual common hand shaker lever 25 (not shown) which affords means to oscillate the assembly of the members 25 and 26 revolvably to and fro about the spindle 20. The outer circular contour 30 of the teeth 27 are dimensioned somewhat less than an arc of 180 degrees, Figure 30 7, to allow clearance so that the assembly of the members 25 and 26 can be revolved to and fro about the spindle 20. The shaker device, by means of the members 25 and 26, is adjustable to a plurality of positions along the spindle 20 so 35 as to fit the requirements of different make standard heaters. Extending downwardly on the member 26 and integral therewith are the lugs 31 provided with the apertures 31' to receive the pin 32, Figure 14, connecting the lugs 31 to the link 33, 40 whose enlarged surface area 34 is provided with the aperture 35 for insertion of the rod 36 which is connected to the lugs 59 of the dome shaped grate 37, Figure 14, thus to transmit the oscillations of the shaker device, Figure 5, to the dome shaped grate unit 37. The foregoing description sets forth the means provided to support, and the method of connecting thereto of the means to impart oscillating motion to the superposed grate structure hereinbefore mentioned, and now 45 to be described.

The superposed grate structure, Figures 11, 12, 13 and 14, consists in its entirety of the base unit 38; mutilated crown gear 49 bearing on the flange 39 of the base 38; a plurality of horizontally disposed rocking or dumping grates 44 which bear on the base unit 38 by means of the brackets 45 and the flange 41; the dome shaped grate unit 37 bearing on the base 38 by means of the lugs 56 which pass through the gear 49 and rest on the flange 39, and a plurality of grate sections 60 substantially upstanding and connected together in the shape of a basket circumscribing the dome grate 37 and the rocking grates 44 and bearing on the journaled members 51 of the said rocking grates 44.

The base unit 38 is preferably molded in two symmetrical segments, for convenience of installation, union of the segments being accomplished by having upwardly projecting flanges 72, diametrically opposite in a vertical plane, molded on a horizontally disposed flange 39 and fastened together with a bolt 76. The abutting ends 74 and 75 of an annular member 87, which is cast integral with the base 38, are positioned diametrically opposite and molded to form a scarf-joint 76

and secured by bolts 77. The base unit 38 is substantially L shaped in cross section, having its inwardly projecting horizontally disposed flange 39 arranged with concentrically disposed slotted apertures 40 formed therein, Figures 11, 12, 13 and 14, which are adapted to register with slotted apertures 15 and 19 in the bars 8 and 9. Thus, the slots 40 accommodate themselves to the adjustability of tie bar assemblies (Figures 1, 2 and 3) hereinbefore described, and function to receive 10 bolts 18 anchoring base 38 to members 8 and 9.

Positioned within the confines of an upstanding flange 41 of the base 38, concentric thereto, and bearing on the upper surface 48 of the flange 39 is an annularly formed mutilated crown gear 49 having its teeth 50 arranged in a plurality of equally spaced groups, each having an equal number and positioned to engage with teeth 54 molded on gear segments 53 that are cast integral with rocker grates 44, Figures 11, 12, 13 and 14. Molded on the vertically disposed flange 41 of base 38 along its upper edge 42 is a plurality of equally spaced semi-circular formed notches 43, (Figures 11 and 14) each of which is co-axial respectively with each of the apertures 47 formed in the upstanding flange 46 of each of the plurality of outwardly projecting brackets 45 cast integral with flange 41. Each pair of apertures 43 and 47 function as bearings for the reception of journaled members 52 and 51 respectively, which are 30 molded integral with each of the horizontally disposed rocker or dumping grates 44 respectively, thus providing means to support rocker grates 44 on base 38, Figures 11, 13 and 14.

Each of the plurality of grate sections 60, Figures 11, 12, 13 and 14, forming the upstanding basket grate, bear at its lower edge 61 on each of the journaled members 51 of the rocker or dumping grates 44 respectively, members 51 functioning in the nature of roller bearings for the grate sections 60. The revolvable motion of said members 51 is in the same direction as the oscillations of grate sections 60, so as to minimize the friction between the contacting surfaces 51 and 61 when in motion. Molded on each grate section 60 above its lower edge 61 (Figures 11 and 14) is a plurality of downwardly projecting gear teeth 62 adapted to engage with the gear teeth 63 molded on each of the gear segments 55 respectively, which are molded integral with the rocker grates 44 and 50 function to transmit oscillations of the rocker grates 44 to the grate sections 60. To insure against undue vertical or horizontal displacement of the grate sections 60 and to eliminate the possibility of disengagement of teeth 62 and 63 during 55 oscillation of the grate system, each grate section 60 has molded thereon a downwardly projecting L shaped lug 64, its horizontally disposed leg 64' projecting inwardly to position under the annular member 87 of the base 38. In order to hold the 60 grate sections 60 in alignment in the form of a basket, there is molded on the adjacent upstanding members 65 and 66 horizontally projecting apertured lugs 67 and 68 respectively, being spaced to position in male and female relation for insertion of the pin 69. Similarly molded on members 65 and 66 at a lower level are apertured lugs 70 and 71 projecting slightly inwardly from contour of grate sections 60 for insertion of pin 72, Figure 14.

The dome shaped unit 37 is provided with a plurality of slotted apertures 37" and also has molded on its convex fuel supporting surface a plurality of outwardly projecting fin shaped members 37' which are adapted to agitate the fuel and 75

ash that collect on its fuel supporting surface when the latter is oscillated. The dome 37 is supported by and is co-axial vertically with base 38 and bears on the upper surface 48 of the flange 39 5 contained therein Figures 11, 13 and 14 by means of a plurality of downwardly projecting and vertically disposed lugs 56 molded to its lower member 86 and arranged concentric with the mutilated gear 49 and spaced respectively to position between the gear segments 53 and within the blank spaces 78 provided on the gear 49. Formed on the outer periphery of the gear 49 and within the angular dimensioned bounds of the blank spaces 78 are notches 79, Figure 13, dimensioned to admit 10 the lugs 56. This affords a means for establishing a fixed relation between the dome shaped grate unit 37 and mutilated gear 49. Thus the gear 49 and the grate unit 37 move as a unit about their vertical common axis upon the oscillation of the dome 37, the surface 48 of the flange 39 functioning as the bearing. The flange 41 is beveled slightly outward on its inner face 58 (Figure 14) to avoid contact with the lugs 56. Two lugs 59, similar to 56, are positioned diametrically opposite and extended downwardly passing through the slotted apertures 84, Figures 13 and 14, formed in the flange 39 of the base 38 and arranged concentrically therewith, terminating below the plane of the underside of the flange 39 (Figure 12), and 15 provided with co-axial apertures 80 to permit insertion of the rod 36, which is rigidly fixed to the extended lugs 59 by its diameter being upset 81, and threads 82 formed thereon to receive nuts 83. The rod 36 is connected to the link 33 and locked 20 in position by a cotter 85, thus affording means to transmit the oscillations of shaker device to the entire superposed grate system including the rockers, basket and dome as hereinbefore described. The circumferential length of slotted 25 aperture 84 is dimensioned to fix the limit of the amount of circumferential oscillation or travel of the extended lugs 59.

It is obvious that while I have illustrated a burner that is circular in form, the same principle 30 may be applied to heaters having other forms of fire boxes, without deviation from the spirit of my invention.

While I have shown in the illustrative embodiment described, link mechanism for actuating the dome shaped grate and through it the shaker and basket shaped grates, it is obvious that a rack and pinion gear or a suitable cam could be substituted for the link mechanism. It is also obvious that the power actuation could be applied directly to the 35 basket shaped or shaker grates and through them to the dome shaped grate. It is also obvious that the operating mechanism may be arranged so that the oscillating motions of the dome and basket formed grates would be in the same instead of 40 opposing directions.

What I claim is:

1. In a fuel burner, a grate structure comprising a substantially dome shaped fuel supporting grate, a plurality of horizontally disposed and circumferentially arranged pivoted fuel supporting rocking grates substantially immediately adjacent to and surrounding said dome shaped grate, manually operated means for simultaneously imparting an oscillating motion to said dome shaped grate 45 about its vertical axis, and to each of said rocking grates about its respective horizontal axis.

2. In a fuel burner, a grate structure comprising a substantially dome shaped fuel supporting grate, a plurality of horizontally disposed and circumferentially arranged pivoted fuel supporting 50

rocking grates substantially immediately adjacent to and surrounding said dome-shaped grate, a basket-shaped fuel supporting grate with outwardly flaring walls co-axial with said dome-shaped grate and substantially concentric with 5 said dome-shaped grate and rocking grates, and a manually operated means for simultaneously imparting an oscillating motion to said dome and basket shaped grates about their common vertical axis and to each of said horizontally disposed 10 rocking grates about their respective horizontal axes.

3. In a fuel burner, a fuel support comprising three grate units including a central substantially dome shaped unit, a substantially horizontal unit 15 disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other and means for effecting simultaneous movement of said central unit and said outer vertical unit about a common axis. 20

4. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other and means for effecting simultaneous movement of said central unit and said outer vertical unit about a common axis in opposite directions. 25

5. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other, and means including a single control device for effecting said movement. 30

6. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other and means for effecting simultaneous movement of said central unit and said outer vertical unit about a common axis, said means including a single control device for effecting said movements. 35

7. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other and means for effecting simultaneous movement of said central unit and said outer vertical unit about a common axis, said means including a single control device for effecting said movements. 40

each other, means for effecting simultaneously a movement of said central unit about its vertical axis and a movement of the separate members of said horizontal unit each about its substantially horizontal axis.

8. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other, means for effecting simultaneously a movement of said central unit about its vertical axis and a movement of the separate members of said horizontal unit each about its substantially horizontal axis, said means including a single control device for effecting said movements.
- 10
- 15
- 20

9. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other, means for effecting simultaneously a movement of said outer substantially vertical unit about a vertical axis and a movement of the separate members of said horizontal unit each about its substantially horizontal axis.

40 10. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other, means for effecting simultaneously a movement of said outer substantially vertical unit about a vertical axis and a movement of the separate members of said horizontal unit each about its substantially horizontal axis, said means including a single control device for effecting said movements.

55 11. In a fuel burner, a fuel support comprising three grate units including a central substantially dome shaped unit, a substantially horizontal unit disposed circumferentially of and substantially

immediately adjacent to said central unit and including separate members each of which is substantially horizontally pivoted, a substantially vertical unit disposed circumferentially of and substantially immediately adjacent to said horizontal unit, said units being movable relative to each other and means for simultaneously effecting a movement of said central unit about its vertical axis in one direction, a movement of said outer substantially vertical unit about an axis common with the axis of said central unit and in an opposite direction thereto and a movement of each of the separate members of said horizontal unit about its substantially horizontal axis. 5 10

12. In a fuel burner, a fuel support comprising 15
three grate units including a central substantially 20
dome shaped unit, a substantially horizontal
unit disposed circumferentially of and substantially
immediately adjacent to said central unit and including 25
separate members each of which is substantially horizontally pivoted, a substantially vertical unit disposed circumferentially of and substantially immediately adjacent to said horizontal unit, said units being movable relative to each other, means for simultaneously effecting a 30
movement of said central unit about its vertical axis in one direction, a movement of said outer substantially vertical unit about an axis common with the axis of said central unit and in an opposite direction thereto and a movement of each of the separate members of said horizontal unit about its substantially horizontal axis, said means comprising a single control device for effecting said movements. 35

13. In a fuel burner, a fuel support comprising three grate units including a central substantially dome shaped unit, a substantially horizontal unit disposed circumferentially of and substantially immediately adjacent to said central unit and including separate members each of which is substantially horizontally pivoted, a substantially vertical unit disposed circumferentially of and substantially immediately adjacent to said horizontal unit, said units being movable relative to each other, means for simultaneously effecting a movement of said central unit about its vertical axis in one direction, a movement of said outer substantially vertical unit about an axis common with the axis of said central unit and in an opposite direction thereto and a movement of each of the separate members of said horizontal unit about its substantially horizontal axis, said means comprising a single control device for effecting said movements, said control device being adjustable as to length and angularity. 35 40 45 50

WILLIAM E. STEINMETZ.
